UNITED STATES PATENT OFFICE.

DAVID J. LA FRANCE, OF SOMERVILLE, MASSACHUSETTS.

CLIP FOR FOUNTAIN-PENS.

1,209,977.

Specification of Letters Patent. Patented Dec. 26, 1916.

Application filed February 15, 1916. Serial No. 78,511.

To all whom it may concern:

Be it known that I, DAVID J. LA FRANCE, a citizen of the United States, residing at Somerville, in the county of Middlesex and State of Massachusetts, have invented certain Improvements in Clips for Fountain-Pens, of which the following description, in connection with the accompanying drawings, is a specification, like reference characters 10 on the drawings indicating like parts in the several figures.

This invention relates to clips for fountain-pens and more particularly to a clip which carries its own means of attachment 15 to the cap.

The qualities desirable in a clip are that it shall be simple and not cumbersome in form, that it shall be easy to attach, that its attachment when made shall be secure, and 20 that it shall be inexpensive to manufacture.

The general object of the present invention is to produce a clip having these qualities.

Referring now to the accompanying drawing, Figure 1 is a perspective showing the clip of the invention holding a pen in the pocket of a garment. Fig. 2 shows in cross-section a cap in place on a fountain-pen, and illustrates more particularly the manner in which the clip is attached, and Fig. 30 is a perspective of the clip before it has been attached to the cap.

Referring first to Fig. 3 the clip comprises a resilient shank 1 of usual form, the lower 35 part of which is designed when the clip has been attached to the cap to lie close to or in contact with the outside of said cap as shown in Fig. 2. Above this shank is a bent portion 3 and above that an extension 5 40 adapted to lie against the inside of the cap. At its top the clip terminates in a softened end 7 which extends at right angles to the extension 5. The cap to which this clip is to be attached is provided with two holes 9 and 45 11 spaced from each other in the direction of the length of the cap, the hole 9 being large enough to permit the bent portion 3 to pass loosely through it. The hole 11 is smaller and may be slightly countersunk 50 from the outside if desired so that the end

of the clip after its attachment will not extend beyond or above the surface of the cap. To attach the clip, the upper end is passed through the larger hole 9 and the clip manipulated to cause the softened end 7 to 55 protrude through the smaller hole 11 with the extension 5 lying along the inside of the cap. The softened end is then clenched as shown in Fig. 2.

The extreme simplicity of the clip is apparent from inspection; its attachment is easy to make and very secure, and its expense of manufacture is small.

Having thus described my invention what I claim and desire to secure by Letters Patent of the United States is:—

1. A fountain-pen cap having formed in the wall thereof two holes spaced from each other in the direction of the length of the cap, and a resilient clip having a bent portion 70 extending loosely through one hole and a soft end extending through the other and clenched against the wall of said cap.

2. A fountain-pen cap having formed in the wall thereof an upper and a lower hole, 75 and a resilient clip of tempered metal having a portion bent in one direction, an upright extension, and a soft end bent in a direction opposite to that of the first-named bend protruding through the upper hole 80 and clenched against the cap, the lower hole being sufficiently large to permit the extension to be inserted through it so as to cause the softened end to protrude through the upper hole preparatory to being clenched. 85

3. As an article of manufacture a clip for a fountain-pen cap said clip being of tempered metal comprising a portion adapted to lie alongside the outer wall of the cap, a portion bent in one direction and adapted 90 to enter a hole in the cap, an upright extension adapted to lie alongside the inner wall of the cap, and a softened end bent in a direction opposite to that of the first-named bend and adapted to extend out 95 through a second hole in the cap and to be clenched in position.

In testimony whereof I have signed my name to this specification.

DAVID J. LA FRANCE.
